COMBINATION GAME

Victor D. Papineau, Athol, Mass.

Application October 7, 1940, Serial No. 360,076

12 Claims. (273—102)

This invention relates in general to an amusement device, and more particularly to a combination game apparatus utilizing targets and movable pieces.

Objects of the invention include the provision of a first target and a second target spaced therefrom, the first target having means for the detachable reception of missiles which are adapted to be impelled toward the second target; the provision of a first target having apertures there-thru for the reception of missiles which may be dislodged and projected toward a second target, such that a score may be obtained for the dislodgement of a missile and a second and cumulative score may be obtained if the dislodged missile strikes a scoring point on the second target; the provision of a pair of spaced targets, each of which is apertured to receive a plurality of missiles, the missiles in one target being adapted to be dislodged by a projectile or other means and the missiles in the second target being adapted to be dislodged by the missiles from the first target; the provision of a pair of spaced targets, one of which is apertured for the reception of a plurality of missiles, said missiles having means whereby they may adhere to the second target when dislodged by a sufficient force from the first target; and the provision of a double target game apparatus such that the player may obtain a score by his skill in striking one target and another score by chance in dislodging a missile or projectile from said target which may or may not strike a scoring point on the other target.

Other objects and advantages of the invention will appear hereinafter.

Reference is to be had to the accompanying drawing, in which

Fig. 1 is an isometric view of a game apparatus embodying the present invention;

Fig. 2 is a sectional view along the lines 2—2 in Fig. 1, parts being broken away;

Fig. 3 is a front elevation of a substitute target; and

Fig. 4 is a sectional view similar to that of Fig. 2, but showing the manner of use of the target of Fig. 3.

Referring to Fig. 1, there is illustrated a front target 1 comprising a generally rectangular thin block of wood, cardboard, or other suitable material. A series of apertures 2 in any desired pattern or form are arranged to extend thru the target and scoring rings 3 of varying denominations, as shown, may be provided around the apertures. A framework 4 extends rearwardly from

5 this target and may be connected thereto by any suitable means. The framework 4 extends and is connected to a second rearward target 5 which, as illustrated in Fig. 1, is exactly like the target 1; that is, the target 5 is provided with apertures 6 and scoring rings 7, the latter being of the same or different scoring values as desired.

10 A plurality of cylindrical pins 8 are provided, these pins having flat heads 9. The pins 8 are of a diameter to slidably or loosely fit into the apertures 2 and 6 in the respective targets 1 and 5.

15 Referring to Fig. 2, it will be seen that the pins 8 are arranged in the target 1 with their heads 9 in the direction of target 5 and the opposite ends of the pins extend forwardly from the target 1. Like pins are also similarly arranged in the apertures 6 of the target 5 with the heads 9 projecting in a direction away from the target 1 and the opposite ends of pins 8 extending toward the target 1.

20 In the utilization of the device, projectiles may be fired from in front of the target 1 so as to strike the extending ends of the pins 8. If a pin is struck by a projectile, it will become dislodged and travel in the direction of the arrows 10 in Fig. 2, and depending upon the force with which it was struck and also to a large degree upon chance it may strike the projecting end of a pin 8 in the rear target 5 dislodging the same. Therefore, it will be seen that depending upon the skill of the player, a pin 8 in the forward target 1 may be struck and converted into a missile which may or may not, depending on chance, strike and dislodge a pin 8 in the rear target 5.

25 Hence, a double score is possible with one shot by the player. Thus, if the pin 8 in the aperture surrounded by the scoring ring 11 in the target 1 is struck and dislodged, the player will get 17 points for his skill. The pin 8 dislodged from this aperture, however, may very well fail to strike a pin in the rearward target since only a slight declination of this missile would suffice to miss the corresponding pin in the ring 17 in the rear target 5.

30 On the other hand, supposing that the pin 8 in the scoring ring 2 of the forward target be dislodged, it may very well strike and dislodge the pin in the scoring ring 50 in the rear target, thus giving the player a score of 52 points. Also, it is quite possible that if the pin in the 50 ring of

35 the forward target is squarely hit with sufficient force, it may dislodge the pin in the scoring ring 50 in the target 5, thus scoring 100 points for the player.

40 It is to be understood that the pins in the for-

ward target may be hit and dislodged by any projectile such as a dart, an arrow or a wooden bullet, or these pins may be dislodged merely by a snap of the fingers.

In Fig. 3, there is disclosed a target 11 which may be a solid board having no apertures, but instead being provided with double scoring rings 12. Target 11 may be substituted for target 5 in the frame 4, and in this case the pins 8 are not used. Darts 13 having heads 14 with pins 15 embedded in their forward ends are placed in the apertures 2 in the target 1. By forcibly ejecting the darts 13 in the direction of the target 11, a double score may be obtained as in the case of the apparatus as shown in Fig. 1, if the dart becomes embedded in any of the scoring rings 12. In this case the total score of the player depends upon his skill in dislodging a dart 13, thus transforming it into a missile, and his luck in striking some scoring ring in the rear target 11.

Having thus described my invention and the advantages thereof, I do not wish to be limited to the details herein disclosed, otherwise than as set forth in the claims, but what I do claim is:

1. In an apparatus of the class described, a target comprising a generally plane element adapted to be set in fixed position, means in said target for the removable reception of missiles or projectiles in a direction normal to said target, and a second target having scoring means and located in the probable projected path of said missiles or projectiles, the two targets comprising a double scoring device, one score being made by removal of a missile or projectile from said first named target and the second score being made by said missile or projectile striking said scoring means on said second target.

2. In an apparatus of the class described, the combination of a target adapted to be set in fixed position and having apertures therethru, and pins, darts, or the like adapted for loose reception in said apertures, with a second target spaced from said apertured target, and scoring means on both targets, whereby a double score may be obtained.

3. In an apparatus of the class described, a pair of spaced targets adapted to be set up in fixed, substantially parallel relation, means in one target adapted for forceful dislodgement and propulsion thereby towards the other target by a blow struck in a direction toward both targets.

4. In an apparatus of the class described, a pair of spaced targets adapted to be set up in fixed, generally parallel relation, means in one target adapted for dislodgement and propulsion towards the other target, and scoring means on said other target effective to indicate scoring points by reason of said first means striking the same.

5. In an apparatus of the class described, a pair of spaced generally parallel targets, pins or darts in one target adapted for being struck out of one target and thereby propelled towards the other target, said pins or darts having means whereby they are adapted to adhere to said other target.

6. In an apparatus of the class described, a pair of spaced targets adapted to be set up in fixed relation, apertures in said targets, and means adapted to be removably mounted in said apertures, whereby the propulsion of said means in one target towards the other may strike and dislodge said means in the other target.

7. In an apparatus of the class described, a frame, a pair of spaced targets adapted to be arranged at opposite ends of said frame, said targets being generally parallel, a series of apertures in one target, pins or darts adapted for removable reception in said apertures, and means on said other target to indicate scores when struck by said pins or darts traveling from said first target.

8. In an apparatus of the class described, a target adapted to be set up in fixed position, an aperture thru said target, a missile adapted to be located in said aperture so that it may be forcefully propelled out of said target when struck from one side of the latter, and a second target adapted to be set up in line with said aperture, whereby said missile, when so forcefully propelled, may strike said second target.

9. An apparatus as recited in claim 8 including means on said missile whereby it may adhere to said second target.

10. An apparatus as recited in claim 8 wherein said second target is provided with an aperture, and means adapted to be located in said last-named aperture to be struck and dislodged by said missile.

11. In a game apparatus, a target board adapted to be set up in fixed substantially vertical position, a horizontal aperture in said board, means adapted to be set in said aperture to be ejected therefrom by a blow from one side of the board, and a second target spaced from and at the other side of said board in position to be struck by said missile when so ejected.

12. In a game apparatus, a generally plane target adapted to be set up in a desired fixed position, an aperture thru said target, a second generally plane target adapted to be set up in a position wherein an element ejected horizontally from said aperture will strike said second target, and scoring indicia on both targets, said indicia being located on corresponding sides of the targets.

VICTOR D. PAPINEAU.
